ELECTRIC SCROLL SAW

Edwin L. Meyer, Bridgeport, Conn.

Application March 16, 1934, Serial No. 715,835

16 Claims. (Cl. 219—29)

This invention relates to an electric scroll saw, and more particularly, to certain improvements thereon.

The tool of the present invention comprises a substantially U-shaped frame having stretched across its open end a high resistance wire which, when heated, preferably to incandescence, may be drawn across a piece of wood to burn a slot therein and in this way cut out designs and do other work usually done with a scroll saw.

A feature of the present invention is the provision of a device of this kind having a pistol grip so disposed that the long legs of the U-shaped frame are held vertically so that the motions of the cutting wire may be in a substantially horizontal plane while the work is held vertically. With tools of this kind as heretofore provided, the work was held horizontally and the cutting element was moved vertically. It has been found that by having the cutting element disposed as above stated, the cutting element may be controlled and the work may be done with greater ease and accuracy. While being reciprocated horizontally, the tool may be moved vertically or laterally as the work progresses without tilting or swinging the frame, for the incandescent wire is operative on all sides.

Another feature of this invention is the provision of a switch on the handle for opening and closing the circuit including the resistance wire. By manipulating the switch, the wire may be made incandescent only when this is actually required. The finger-piece for the switch is in the shape of a trigger and is carried by the handle or grip in the position usually occupied by a trigger in a pistol.

Another feature of this invention is the provision of means for controlling the operative length of the wire. Should it be found that because of the thickness or characteristic of the wood worked upon the wire cools too rapidly upon contact with the wood, this resistance wire in effect may be shortened so as to increase its resistance and raise its temperature. This is of great practical importance, since, by a simple adjustment, the desired working temperature of the wire can be obtained.

A further feature of the present invention is the provision of means for maintaining the wire taut even though it elongates upon being heated, and yet avoid undue bowing of the wire when applied to the work. Heretofore it was proposed to compensate for the expansion and contraction of the wire by making the frame itself resilient. With this provision, however, when the wire is

applied to the wood, bowing of the wire is permitted with the result that a flat-bottom cut is not produced. According to the present invention, the frame is made relatively rigid and one end of the wire is yieldingly mounted, but the yielding mounting for that end of the wire operates efficiently only when pulled in a direction parallel to the wire, and, when a lateral pressure is applied thereto, as when the wire engages the work, it becomes relatively nonyielding.

A further feature of the present invention is the provision of a light carried by the frame or handle and shining in the direction of the work for illuminating the work to facilitate the following of guide lines drawn thereon. According to the present invention, the light is kept on so long as the tool is connected to a source of current and is not affected by the operation of the switch controlling the passage of current to the cutting wire.

One of the more important features of the present invention is the employment of supply current of very low potential and high current, and the heating wire employed is suited to these conditions. The current supply is preferably obtained from a transformer connected to alternating house current. By employing current having a potential of a fraction of a volt which has been found satisfactory, there is avoided the danger of the user being shocked or injured by short-circuiting the terminals with part of his body when applying or adjusting the wire, or by casual contact in the use of the device.

Other features and advantages will herein-after appear.

In the accompanying drawing—

Figure 1 is a side elevation of the electric saw of the present invention.

Fig. 2 is a sectional view taken on the line 2—2 of Fig. 1, and showing the means for securing the end of the wire remote from the handle.

Fig. 3 is a detail view, partly in section, taken on the line 3—3 of Fig. 1.

Fig. 4 is a sectional view taken on the line 4—4 of Fig. 1.

Fig. 5 is a vertical sectional view taken on the line 5—5 of Fig. 1.

Fig. 6 is a transverse section through the handle, taken on the line 6—6 of Fig. 1.

Fig. 7 is a sectional view showing the means for securing the end of the wire adjacent the handle.

Fig. 8 is a diagrammatic view, showing the means for supplying current to the tool.

Fig. 9 is a plan view of another form of clamp for holding the remote end of the wire.

As shown in the accompanying drawing, the electric saw of the present invention comprises a relatively large U-shaped frame 10 having an upper horizontal leg 11 and vertical legs 12. One of the legs 12 is made somewhat shorter than the other, and has its end fitting in a socket 13 in a handle 14 having a pistol grip 15. The pistol grip includes a central metal portion 16 and side portion 17 of wood. Between these there is provided a chamber or opening 18 through which pass current supply wires 19. These wires enter the handle through a bushed opening 20 at the bottom of the pistol grip.

At the lower end of the longer leg 12 of the frame there is secured a T-shaped bearing member 21 having a square hole 22 in which there is slidably mounted a square rod or slide 23. One end of this rod carries a nut 24 against the head of which bears a spring 25 tending to move the slide in the direction of the arrow shown in Fig. 1. The other end of the slide carries a flange 26 limiting the movement of the slide in the direction of the arrow shown in Fig. 1. Beyond the flange 26, the slide has a flat portion or shelf 27 on which is carried a clamp 28 having a screw 29 bearing on one side of the shelf 27 and a saddle 30 located at the opposite side of the shelf.

This clamp or binding post is intended to secure to the slide 23 a high resistance wire 31 which is the cutting element of the present invention. When the wire is slid between the shelf 27 and saddle 30 and the screw 29 rotated, the saddle is drawn up to securely clamp the wire to the shelf. The shelf may have a V-shaped notch 32 as shown in Fig. 2, to locate the wire centrally of the rod.

The opposite end of the wire 31 is secured in place by a similar clamp 28, but in this case the shelf 27 is formed on a stud 33 having a head 34 engaging the inner end of a bushing 35 mounted in a screw-threaded portion 36 in the metal member 16 of the handle. The bushing 35 is made of insulating material and is applied to the stud, before the clamp 28 is mounted on the shelf 27, and serves to insulate the stud, clamp and the near end of the wire 31 from the handle.

The remote end of the wire 31 is connected to the source of current through the slide 23, bearing 21, frame 10, and metal member 16 of the handle by means of a binding screw 37 carried by the portion 16 and connected to one wire 38 of the cable supplying the device with current. The other or near end of the wire 31 is connected to a source of current when desired by a switch blade 39 connected to a binding post 40 carried by and insulated from the handle and connected to the other wire 41 of the cable supplying current to the device. The switch blade 39 normally occupies the position shown in Fig. 1 and is spaced from the head 34 of the stud 33 carrying the near end of the wire. To move the switch blade into contact with the head of the stud, there is provided a trigger 42 pivoted at 43 and having an arm 44 engaging the switch blade and in position to move the switch blade into contact with the head 34. The trigger 42 is placed on the handle 15 in the position corresponding to the trigger of a pistol, and hence, by merely pressing on and releasing the trigger 42, the user may make the wire 31 incandescent or not at will.

When the wire 31 becomes heated and incandescent, it naturally increases in length or elong-

ates. This would cause it to sag unless provisions were made to avoid it. According to the present invention, this is done by securing the remote end of the wire 31 on the slide 23 in such a way that the spring 25 tends to move the slide in the direction of the arrow, thereby keeping the wire under tension and taut. When, however, the wire is applied with some force to the work, it is undesirable that the wire bow substantially, and accordingly at this time the slide should not move easily. By making the slide square, the tendency for the slide to move when the wire is applied to the work is avoided, the lateral pressure on the slide causing the flat side of the slide to engage the flat surface of the hole 22 and bind in whatever position it may at that time be.

By providing these means for holding and controlling the remote end of the resistance wire, the U-shaped frame 10 may be made substantially rigid so that it may impart true and intended motion to the resistance wire in tracing a design.

In order to facilitate the tracing of the design with the resistance wire 31, the saw, according to the present invention, is provided with a lamp 45 mounted in a socket 46 in the metal part 16 of the handle and extending into the chamber 18. The center contact of the lamp is engaged by an upper extension 47 on the switch blade 39. It will thus be seen that the lamp 45 will glow continuously even though the switch blade 39 is disengaged from the head 34 of the wire holding stud 33.

In use, the tool is grasped by the handle grip 15 while one finger engages the trigger 42. While the frame 10 is held upright, the wire 31 is applied to the edge of the wood which is also held upright. The trigger 42 is then operated to close the circuit and causing the wire 31 to become incandescent, or at least hot enough to cut the wood. When the wire is so conditioned, it is drawn back and forth over the wood following the outline of the design to be cut. The back and forth motion of the wire is necessary, since, according to the present invention, the cross section and heat of the wire is such that if allowed to remain in one position, the portion in contact with the wood would cool so rapidly as not to burn. By moving the wire back and forth, a hot portion of the wire is constantly being applied to the wood, and the portion just leaving the wood has an opportunity to become reheated.

In practice, it is sometimes desired to have the wire 31 hotter than other times. For this purpose, the wire 31 is made longer than the normal distance between the clamp 28, and a portion of the end of the wire 31a is allowed to project beyond the clamp in the passage 23a in the slide 23. If it is desired to make the wire hotter than normal, the screw on the slide 23 is loosened and the slide is pulled out farther than normal, thus shortening the wire electrically, the surplus end 31a projecting further into the opening 23a. If a cooler wire is desired, reverse operations are performed.

As diagrammatically illustrated in Fig. 8, the wires 38 and 41 are connected to a secondary winding 47 on a transformer 48 having a primary winding 49 connected to the commercial power line 50. The ratio of the windings 47 and 49 is such that an electromotive force of somewhat less than one volt and proportionately high current is impressed on the circuit including the wires 38 and 41 and the heating wire 31. Currents of such values are not harmful, and accord-

ingly the saw may be handled anywhere desired, or may be contacted with casually without shock or injury, except, of course, by contacting directly the incandescent wire 31 which would produce a 5 burn.

In Fig. 9, there is shown a modified form of clamp for holding the remote end of the resistance wire 31. In this form, there is provided a pair of jaws 51 pivoted on the reduced end 52 of the longer leg 12 of the frame and having opposite the pivot 52 arms 53 across which there is connected a spring 54 tending to pull the arms 53 and jaws 51 together so that the latter may tightly grip the end of the resistance wire 31. To release the jaws, a pair of toggle-links 55 are connected to the ends of the arms 53, and at the pivot point 56 of the toggle-links there is provided a finger-piece 57.

Upon applying pressure to the finger-piece 57, the toggle-links 55 move toward straightened or parallel positions, and, in doing so, spread the arms 53 and jaws 51 to permit the removal or insertion of the end of the resistance wire 31 between them. Upon release of the finger-piece 57, the spring 54 draws the jaws 51 together. By having the actuating device for the jaws in the form of the toggle, the jaws may be easily opened in spite of the fact that the spring 54 is very strong.

The form of the invention shown in Fig. 9 is particularly advantageous when the work to be done requires that the wire 31 be passed through a perforation or drilled hole in the work, for in this case the wire 31 may be threaded through the hole and easily and quickly clamped in the remote or opposite end of the frame, the near end of the wire being attached to the binding post on the handle.

Variations and modifications may be made within the scope of this invention and portions of the improvements may be used without others.

Having thus described the invention, what is claimed as new and for which it is desired to obtain Letters Patent, is:—

1. An electric scroll saw comprising a rigid U-shaped frame; a resistance wire; and binding posts on opposite legs of the frame having thumb screws for clamping the resistance wire and holding the wire across the open end of the frame, one of said binding posts being yieldingly and slidably mounted on the leg of the frame carrying it and holding the resistance wire taut as it expands and contracts incidental to the heating and cooling of the wire.

2. An electric scroll saw comprising a rigid U-shaped frame; a resistance wire; and binding posts on opposite legs of the frame having thumb screws for clamping the resistance wire and holding the wire across the open end of the frame, one of said binding posts being yieldingly mounted on the leg of the frame carrying it and holding the resistance wire taut as it expands and contracts incidental to the heating and cooling of the wire, said binding post being mounted on a slide and said slide having a bearing on the leg of the frame on which it is carried, and a spring normally tending to move the slide and applying a stretching action to the wire to maintain it taut.

3. An electric scroll saw comprising a rigid U-shaped frame; a resistance wire; and binding posts on opposite legs of the frame having thumb screws for clamping the resistance wire and holding the wire across the open end of the frame, one of said binding posts being yieldingly mounted on the leg of the frame carrying it and holding the resistance wire taut as it expands and con-

tracts incidental to the heating and cooling of the wire, said binding post being mounted on a slide and said slide having a bearing on the leg of the frame on which it is carried, and a spring normally tending to move the slide and applying a stretching action to the wire to maintain it taut, said slide and bearing therefor being square in cross-section whereby the slide tends to jam in the bearing when pressure is applied laterally to the slide to prevent excessive bowing of the resistance wire when applied to the work.

4. An electric scroll saw comprising a rigid U-shaped frame; a resistance wire; and binding posts on opposite legs of the frame having thumb screws for clamping the resistance wire and holding the wire across the open end of the frame, one of said binding posts being yieldingly mounted on the leg of the frame carrying it and holding the resistance wire taut as it expands and contracts incidental to the heating and cooling of the wire, said binding post being mounted on a slide and said slide having a bearing on the leg of the frame on which it is carried, and a spring normally tending to move the slide and applying a stretching action to the wire to maintain it taut, the engagement between the slide and its bearing being such as to tend to cause the slide to jam and remain held against longitudinal movement when lateral pressure is applied to the slide.

5. An electric scroll saw comprising a rigid U-shaped frame; a resistance wire; and binding posts on opposite legs of the frame for clamping the resistance wire across the open end of the frame, one of said binding posts being yieldingly mounted on the leg of the frame carrying it and holding the resistance wire taut as it expands and contracts incidental to the heating and cooling of the wire, said binding post being mounted on a slide and said slide having a bearing on the leg of the frame on which it is carried, and a spring normally tending to move the slide and applying a stretching action to the wire to maintain it taut, said slide having a passage in line with the wire to receive the end of the wire when the slide is moved longitudinally with relation to the wire to shorten the effective length of the wire and thereby cause the wire to be brought to a greater degree of incandescence when energized.

6. An electric scroll saw comprising a substantially U-shaped frame; a handle secured to one of the legs of the U-shaped frame; a resistance wire stretched across the open side of the frame; a pair of binding posts, one securing and electrically connecting one end of the resistance wire to the frame and the other securing the other end of the resistance wire to the handle and insulated therefrom and from the frame; a current supply wire connected to the frame; a switch blade; a current supply wire connected to the switch blade; and a finger piece for moving the blade into engagement with the binding post which is insulated from the handle and frame.

7. An electric scroll saw comprising a substantially U-shaped frame; a handle secured to one of the legs of the U-shaped frame; a resistance wire stretched across the open side of the frame; a pair of binding posts, one securing and electrically connecting one end of the resistance wire to the frame and the other securing the other end of the resistance wire to the handle and insulated therefrom and from the frame; a current supply wire connected to the frame; a switch blade; a current supply wire connected to the switch blade; and a finger piece for moving the

blade into engagement with the binding post which is insulated from the handle and frame, said handle being in the form of a pistol grip and said finger piece for the switch being trigger-like and pivotally mounted on the handle.

8. An electric scroll saw comprising a substantially U-shaped frame; a handle secured to one of the legs of the U-shaped frame; a resistance wire stretched across the open side of the frame, 10 said handle having a chamber therein open at the bottom; current supply wires entering the chamber through said opening and terminating in said chamber, one of said wires being connected to the frame and from the frame to one end of the 15 resistance wire; a switch in said chamber for connecting the other wire to the other end of the resistance wire; and a lamp carried by the handle connected to said ungrounded current supply wire independently of said switch.
- 20 9. In a device of the character described, an electric resistance wire forming a burner element; a frame in which said wire is carried and having an open side across which the said wire is stretched, said frame having a hand grip the axis of 25 which forms an angle of greater than 30° with the axis of the wire by means of which hand grip the frame is manipulated to draw the resistance wire over the work; means for supplying low voltage high amperage currents to said wire to 30 heat the same, said means including a transformer supported independently of said frame and having a primary connected to a source of house current, a secondary, flexible wires connecting the secondary with said resistance wire, 35 and a switch carried by the frame to open and close the circuit including said secondary and said resistance wire; and a finger-piece for said switch carried by the hand grip to be operated by the finger of the operator's hand holding the hand 40 grip to instantly open and close the circuit leading to the resistance wire.
10. In a device of the character described, an electric resistance wire forming a burner element; a frame in which said wire is carried and to which 45 one end of the wire is electrically connected, having an open side across which the said wire is stretched and having a wire holder insulator for the frame, said frame having a hand grip by means of which the frame is manipulated to draw 50 the resistance wire over the work; means for supplying low voltage high amperage currents to said wire to heat the same, said means including a transformer having a primary connected to a source of house current, a secondary, flexible 55 wires connecting the secondary with said resistance wire, one of said wires being electrically connected to the frame, and a switch carried by the frame to open and close the circuit including said secondary, one of said flexible wires, said resistance 60 wire, the frame, and the other flexible wire at a point between the flexible wire and insulated resistance wire holder; and a finger-piece for said switch carried by the hand grip to be operated by the finger of the operator's hand holding the hand 65 grip to instantly open and close the circuit leading to the resistance wire.

11. In a device of the character described, an electric resistance wire forming a burner element; a frame in which said wire is carried and having an open side across which the said wire is stretched, said frame having a hand grip the axis of which forms an angle of greater than 30° with the axis of the wire, by means of which hand grip the frame is manipulated to draw the resistance wire over the work; means for supplying 70

low voltage high amperage currents to said wire to heat the same, said means including a switch carried by the frame; and a finger-piece for said switch carried by the hand grip to be operated by the finger of the operator's hand holding the hand grip to instantly open and close a circuit supplying current to the resistance wire.

12. An electric scroll saw comprising a rigid U-shaped metal frame; a resistance wire adapted to be removably carried across the open side of 10 the frame; manually releasable wire-gripping means on opposite legs of the frame; means for mounting one of said wire-gripping means on one leg of the frame in position fixed against movement axially of the wire; means for mounting the other wire-gripping means on the other leg of the frame for slidable movement relative to the frame and axially of the wire; resilient means normally tending to cause the slidably mounted wire-gripping means to move axially of 20 the wire away from the other wire-gripping means to hold the wire gripped thereby taut, said slidably mounted wire-gripping means being in electrical engagement with the frame; means for insulating the fixed wire-gripping means 25 from the frame; and means for supplying current to the resistance wire through said frame.

13. An electrical scroll saw comprising a U-shaped metal frame; a resistance wire adapted to be removably carried across the open side of 30 the frame; manually releasable wire-gripping means on opposite legs of the frame; means for mounting one of said wire-gripping means on one leg of the frame in position fixed against movement axially of the wire; means for mounting the other wire-gripping means on the other leg of the frame for slidable movement relative to the frame and axially of the wire; resilient means normally tending to cause the slidably mounted wire-gripping means to move axially 35 of the wire away from the other wire-gripping means to hold the wire gripped thereby taut, said slidably mounted wire-gripping means being in electrical engagement with the frame; means for insulating the fixed wire-gripping 40 means from the frame; flexible wires for supplying current to said resistance wire, one of said wires being in electrical engagement with the frame; and manually operable means for electrically connecting the other wire to the fixed 45 and insulated wire-gripping means.

14. An electric scroll saw comprising a U-shaped metal frame; a resistance wire adapted to be removably carried across the open side of the frame; manually releasable wire-gripping 55 means on opposite legs of the frame; means for mounting one of said wire-gripping means on one leg of the frame in position fixed against movement axially of the wire; means for mounting the other wire-gripping means on the other leg of the frame for slidable movement axially 60 of the wire; resilient means normally tending to cause the slidably mounted wire-gripping means to move axially of the wire away from the other wire-gripping means to hold the wire gripped 65 thereby taut, said slidably mounted wire-gripping means being in electrical engagement with the frame; means for insulating the fixed wire-gripping means from the frame; a hand grip on the side of the frame carrying said fixed wire-gripping 70 means; flexible wires extending into and through said hand grip for supplying current to said resistance wire, one of said wires being in electrical engagement with the frame; and manually operable means on the hand grip for electric- 75

esally connecting the other wire to the fixed and insulated wire-gripping means.

15. An electrical scroll saw comprising a U-shaped frame; a resistance wire adapted to be 5 removably carried across the open side of the frame; manually releasable wire-gripping means on opposite legs of the frame; means for mounting one of said wire-gripping means on one leg of the frame in position fixed against movement axially of the wire; means for mounting the 10 other wire-gripping means on the other leg of the frame for slidable movement relative to the frame and axially of the wire; resilient means normally tending to cause the slidably mounted wire-gripping means to move axially of the wire 15 away from the other wire-gripping means to hold the wire gripped thereby taut; and means for supplying current to said resistance wire, one of the wire-gripping means including a pair of jaws resiliently urged together to grip the wire, and a button to spread the jaws to receive the 20 wire.

16. An electric scroll saw comprising a U-shaped frame; a resistance wire adapted to be 25 removably carried across the open side of the

frame; manually releasable wire-gripping means on opposite legs of the frame; means for mounting one of said wire-gripping means on one leg of the frame in position fixed against movement axially of the wire; means for mounting the 5 other wire-gripping means on the other leg of the frame for slidable movement relative to the frame and axially of the wire; resilient means normally tending to cause the slidably mounted wire-gripping means to move axially of the wire 10 away from the other wire-gripping means to hold the wire gripped thereby taut; and means for supplying current to said resistance wire, the 15 slidable wire-gripping means having a pair of wire-gripping jaws normally urged toward each other to grip the end of the wire, and means connected to the jaws including a finger-piece adapted to be moved in a direction toward the wire to open the jaws to receive the wire and at the same time to cause the wire-gripping means 20 to slide toward the wire against the tension of the means normally urging it away from the wire.

EDWIN L. MEYER.
